UNITED STATES PATENT OFFICE.

ROE C. HAWKINS, OF LONG BEACH, CALIFORNIA.

STANDING-VALVE PULLER.

Application filed October 23, 1926. Serial No. 143,716.

In standing valve pullers heretofore used the coupling members on the plunger and standing valve were rigidly connected to their respective members, and this construction resulted in serious damage to the said coupling members when the plunger would strike against the standing valve.

An object of my invention is to provide a yieldable puller for the standing valve of a pump.

Another object is to provide a yieldable puller which will also act to control the balls in the pump valves.

A further object is to provide a puller which will be positively engaged by the pump plunger so that the standing valve cannot fall back into the well after it is once engaged.

Other objects, advantages and features of invention may appear from the accompanying drawing, subjoined detailed description, the appended claims or in the operation of my device.

In the drawing:

Fig. 1 is a longitudinal sectional view of my puller.

Fig. 2 is a longitudinal sectional view of the puller in engaging position.

Fig. 3 is a longitudinal sectional view of a modified form of puller.

Fig. 4 is a plan view of the puller sleeve.

Fig. 5 is a plan view of the tube which is secured to the pump plunger.

Referring more particularly to the drawing:

My invention is applicable to the usual pump construction including the working barrel 1, the plunger 2 and the standing valve 3. A square post 4 rises from the standing valve 3 and is threaded in the top thereof, said post having a head 5 formed on the top thereof. A sleeve 6 is slidably mounted on the square post 4 and a spring 7 surrounds said post and yieldably urges said sleeve upwardly. The sleeve 6 is formed with outwardly extending wings, 8 and 9, the wing 8 being greater in width than the wing 9, the purpose of which will be further described.

A tube 10 screws into the lower end of the plunger 2 and depends therefrom. It is desirable under certain conditions that a valve such as the one shown at 11 be positioned in the lower end of the plunger 2. The top of the tube 10 is provided with an opening 12 therein, said opening conforming in shape

to the sleeve 6, thus it will be seen that in one position only will the sleeve 6 enter the opening 12. In operation the plunger 2 is reciprocated in the working barrel, in the manner well known to the art and if the tube 10 should engage the sleeve 6, said sleeve will merely slide downwardly on the post 4 against the urge of the spring 7 and will cause no damage to the engaging parts.

When it is desired to pull the standing valve, the plunger 2 is lowered until the tube 10 rests on the standing valve as shown in Fig. 2. In this position the spring 7 is compressed and urges the sleeve 6 upwardly. Upon rotation of the plunger 2 the opening 12 will register with the sleeve 6 and the spring will then urge the said sleeve upwardly to the position shown in dotted lines, Fig. 2. A slight reverse turn of the plunger 2 will then securely lock the sleeve 6 in position over the tube 10, and the standing valve may be pulled.

When a lower valve 11 is used as shown in Fig. 1 the post 4 will extend upwardly through the opening 12, unseating the ball 13 in the extreme lower position of the plunger; thus insuring the proper operation of the valve. As shown in Fig. 3 the square post 14 is slidably mounted in the top of the standing valve 3 and a spring 15, acting against a collar 16 normally holds said post in raised position. The sleeve 6 as previously described as slidably mounted on the square post 14 and a spring 17 normally urges said sleeve upwardly against the tube 10. It will be evident that in the lowered position of the plunger the top of the tube 10 will engage the sleeve 6, compressing the springs 15, 17 and urging the lower head 18 of the post 14 against the standing valve ball 19; thus positively seating said ball and, simultaneously the top head 20 will engage the ball 13 of the valve 11, unseating said last named ball. Thus at each stroke of the plunger the standing and traveling valves are positively actuated.

Having described my invention, I claim:

1. In a pump comprising a standing valve and a plunger, a post rising from said standing valve, a sleeve yieldably mounted on said post and means on said plunger adapted to engage said sleeve, whereby the standing valve may be pulled.

2. In a pump comprising a standing valve and a plunger, a post rising from said standing valve, a sleeve yieldably mounted on said

post, a tube depending from said plunger, said tube having an opening therein, adapted to receive said sleeve; whereby the standing valve may be pulled.

- 5 3. In a pump comprising a standing valve and a plunger, a post rising from said standing valve, a sleeve slidably and nonrotatably mounted on said post, a spring engaging said sleeve, a tube depending from said plunger, said tube having an opening therein, adapted to receive said sleeve.

4. In a pump comprising a standing valve and a plunger, a post rising from said standing valve, a sleeve slidably and nonrotatably

- 15 mounted on said post, a spring engaging said sleeve, a tube depending from said plunger, said tube having an opening therein, adapted to receive said sleeve, said sleeve being formed with outwardly extending 20 wings, one of said wings being greater in width than the other, and said opening being the same shape as said sleeve.

5. In a pump comprising a standing valve and a plunger, a post slidably mounted in 25 said standing valve, means holding said post in a normal raised position, a sleeve on said post, resilient means engaging said sleeve

and means on said plunger adapted to engage said sleeve; said post being adapted to engage the ball in said standing valve in 30 the lowered position of the plunger.

6. In a pump comprising a standing valve and a plunger, a post slidably mounted in said standing valve, a spring normally urging said post to a raised position, a sleeve 35 on said post, a spring engaging said sleeve, a tube depending from said plunger, said tube having an opening therein, adapted to receive said sleeve; whereby the standing valve may be pulled, said post being adapted 40 to engage the ball in said standing valve in the lowered position of the plunger.

7. In a pump comprising a standing valve, a plunger and a valve in the lower part of said plunger, a post slidably mounted in 45 said standing valve, a sleeve slidably mounted on said post, resilient means engaging said sleeve, means on said plunger adapted to engage said sleeve, said post being adapted to engage the balls in the standing valve 50 and plunger valve in the lowered position of said plunger.

In testimony whereof, I affix my signature.
ROE C. HAWKINS.
